[57] CLAIM

The ornamental design for a screwdriver handle, as
shown and described.

DESCRIPTION

FIG. 1 is a perspective view of a screwdriver handle
showing my new design;

FIG. 2 is an alternate perspective view thereof;

FIG. 3 is a bottom plan view thereof;

FIG. 4 is a top plan view thereof;

FIG. 5 is a side elevational view thereof, taken along
line 5—5 of FIG. 3;FIG. 6 is a side elevational view thereof, taken along
line 6—6 of FIG. 3;FIG. 7 is a perspective view of a modified embodiment
thereof;

FIG. 8 is an alternate perspective view of FIG. 7;

FIG. 9 is a bottom plan view of FIG. 7;

FIG. 10 is a top plan view of FIG. 7;

FIG. 11 is a side elevational view thereof, taken along
line 11—11 of FIG. 9; and,FIG. 12 is a side elevational view thereof, taken along
line 12—12 of FIG. 9;The broken line showing of the blade is for illustrative
purposes only and forms no part of the claimed design.
